OTTO ROTH, OF BERLIN-LICHTERFELDE, GERMANY

RAZOR BLADE

Application filed July 30, 1928, Serial No. 296,384, and in Germany March 19, 1928.

My invention relates to razor blades, more particularly those having two cutting edges, such as are used with the so-called safety razors, in which when in use, the blade is clamped over an arched indented guard plate.

Razor blades of this kind are made as thin as possible both to improve their cutting capacity and to facilitate bending them over the arched guard plate. A certain limit is set to this effort by the fact that the resistance of the blade to bending stresses, more particularly to those in planes parallel to the cutting edge, must not be too small, as otherwise the blade may easily be fractured, especially when being clamped in the safety razor. In this respect the middle parts of the blade, which are already weakened by the holes for the pins of the safety razor, are specially endangered. Hence, in practice it is of no use to grind the whole of the blade surface evenly to the same thickness. It is also not possible to grind down the blade in separate stripes running parallel to the cutting edge, as this would produce dangerous cross sections extending over the entire length of the blade, which might easily cause the blade to break along the said stripes.

Now, I have found that these disadvantages may be avoided by the blade being ground in zig-zag, serpentine or like stripes such that the weakening zones caused by the grinding do not extend straight from end to end of the blade and therefore cannot be the cause of fractures even when the blade is heavily stressed in the transverse direction. This effect can be still further increased by the grinding stripes being off-set with respect to one another on the two sides of the blade.

With these and other objects in view, the nature of which will more fully appear as the description proceeds, my invention consists in the special formation and arrangement of the grinding zones of the blade.

In the accompanying drawings, which represent to a greatly enlarged scale two preferred embodiments of my invention, Fig. 1 shows one half of a blade made in accordance with the invention. Fig. 2 is a cross section on the line II-II of Fig. 1. The illustration in Fig. 2 is out of proportion in order to

make it more clear; in reality the dimensions as regards the thickness are considerably less as compared with the breadth of the blade. Fig. 3 shows in the same mode of representation as Fig. 1 a modification.

In the drawing the places 1 and 1^a which are ground in accordance with the invention, are shaded, while the places or zones 2 and 2^a which substantially retain their original level, are left plain. As will be seen from Figure 1, the ground stripes extend in a zig-zag or serpentine fashion in the longitudinal direction of the blade on both sides of the same. The middle part of the blade, which contains the holes 3 and 4 for slipping over the pins of the safety razor is preferably left, at least on one side, in its original thickness.

The outer grinding stripes 1^a of the side of the blade visible in Figure 1 merge directly into the cutting edges 5, 5. Unground stripes may of course adjoin the cutting edges, as is the case in the constructional example shown at 2^a in Fig. 3.

It will be seen that within the range of the ground places, except at the extreme edges, every line drawn parallel to the cutting edge alternately strikes thinly ground and unground parts of the blade, in other words that there are no weakening lines extending right along in the longitudinal direction of the blade. In this arrangement not only the cutting edges themselves but the parts of the blade lying in the vicinity are of the desired slight thickness desirable for having a good cutting capacity, and the flexibility of the blade as a whole is considerably increased, as compared with the case of a blade ground in the ordinary way.

The grinding stripes 1, 1^a may, of course, have a different form and be provided in a greater or smaller number and in a different position. Or they may be made broader or narrower; they also need not extend throughout the entire length of the blade. They may, as for instance as shown in Fig. 3, be more serpentine or more like a sine curve. Such a form is obtained, for instance, if the grinding be carried out in such a manner that the grinding discs during the passage of the blade in its longitudinal di-

rection perform for instance a reciprocating motion derived from a circular motion through the intermediary of a crank or the like.

5 As will be seen from Figure 2, the grinding stripes 1, 1^a, may be off-set with respect to one another on the two sides of the blade, such that opposite a grinding stripe on one side there is a stripe of untouched material 10 on the other side, so that the weakenings caused by the grinding do not have an additive effect.

The grinding stripes may, as indicated in Fig. 3, also be off-set with respect to one another in such a way that the projections of 15 two serpentine stripes laying opposite each other on the two sides of the blade will cross one another.

The use of blades ground in accordance 20 with my invention has the further advantage that, in contradistinction to the blades as hitherto generally used, which bend particularly readily in the middle where the holes lie, they bend substantially equally over 25 the entire width of the guard plate, as, owing to the peculiar form of the grinding stripes, the material is equalized in the separate clamping planes. By this means a considerably more favourable cutting angle is produced at the cutting edges.

I claim:

1. A blade for safety razors having on both sides a plurality of thinner ground zones in the form of wave-lines extending substantially in the longitudinal direction of the 35 blade.

2. A blade for safety razors having on both sides a plurality of thinner ground zones in the form of wave-lines extending substantially in the longitudinal direction of the 40 blade, the ground zones of the one blade side being off-set with respect to the ground zones of the other blade side.

3. In a blade for safety razors, having holes 45 in the longitudinal middle line groups of thinner ground places on each side of said middle line and having the form of to and fro stripes extending in the longitudinal direction of the blade.

50 4. In a blade for safety razors, having holes in the longitudinal middle line, a plurality of thinner ground places having the form of wave-like stripes extending substantially in the longitudinal direction of the blade symmetrically at each side of said middle line.

In testimony whereof I affix my signature.
OTTO ROTH.
